BLANKING APPARATUS FOR WHEELS

Application filed October 11, 1929. Serial No. 398,868.

This invention relates to a molding means and in particular relates to a means for blanking spoked wheels from loose, bulky material. An object of the invention is the provision of improved means for this service.

In the molding of wheels I have sometimes heretofore used a moderately dense material such as wood or fibrous sheet laminæ which was reduced by about half its original volume in the molding operations. For this work a single mold may be made with sufficient depth to perform the required compression. Such a mold may also be conveniently arranged to apply the necessary heat for molding.

For a molding operation of this sort the material must be preliminarily shaped to conform quite closely to the shape of the final mold. When wood is the material used, it must be sawed, bent or built up to conform. When fibrous laminæ is used it must be wound into tight rolls or assembled in blanks or blocks to conform. When rubber or similar material is used it is usually cut into strips which are laid in the mold or wound about a core.

When wood or similar material was used there were a number of expensive operations to get out the blanks ready for placing in the molds. With fibrous laminæ, the winding or other forming operations were expensive and entailed the loss of much of the material as scrap. Sometimes as much as a third of the material was lost in this way. The forming up of the blank of rubber or like material to make it conform to the mold so as to produce a homogeneous uniform wheel also involved expensive and tedious preliminary operations.

To avoid these difficulties I have found a way to use material of heterogeneous shape and size such as chips, shavings, dust, pulp, chopped sheets and the like. This material in its very nature is much more bulky and must be compressed through a much greater range of size than material heretofore used. It is within the range of possibility to make a single heated press of sufficient depth and stroke to make the final wheel from such ma-

terial in one operation but I have found that great economies may be effected and a better wheel produced by making the wheel in two molding operations. In the first operation the material is compressed and formed or blanked to conform to the outlines of the final mold and in the second operation this blank is further compressed and cured under heat and pressure to form the finished wheel.

Herein is disclosed apparatus intended to perform the first operation. This apparatus is designed to operate rapidly, effectively and economically and to produce a blank which is homogeneous and uniform in all its parts. In making a reticulated molded structure such as a spoked wheel, problems are encountered which are not found in molding solid articles by reason of the fact that in a reticulated structure care must be exercised not only to make the parts sufficiently strong within their own length but to make the connecting joints between the several parts sufficiently strong. The present apparatus has proved successful to these ends. In a copending application, Serial Number 398,870, filed October 11, 1928 the method of making wheels with this apparatus and the blank formed thereby is described and claimed.

The nature and objects of the invention will be better understood from a description of an illustrative embodiment of the invention when considered in connection with the accompanying drawings thereof, in which:

Figure 1 is a front elevation of the assembled press, showing one container or pot between the ram and head ready for compressing and the other pot swung outward for loading;

Figure 2 is a side elevation;

Figure 3 is a top plan view;

Figure 4 is a vertical section taken on line 4—4 of Figure 3;

Figure 5 is a similar section but taken with the compression stroke completed;

Figure 6 is a horizontal section taken on line 6—6 of Figure 4;

Figure 7 is a vertical section of the container when partly filled;

Figure 8 is a similar view after reinforcement and a hub filler have been inserted;

Figure 9 is partial vertical section taken slightly behind the plane of Figure 8;

Figure 10 is an enlarged horizontal section on the line 10—10 of Figure 9; and

5 Figure 11 is a horizontal section taken on line 11—11 of Figure 4.

Referring to Figure 1 of the drawings, the apparatus comprises a hydraulic cylinder 20, a ram in the form of a platform 21 actuated by a piston working in the cylinder, and a head 22 connected to the cylinder 20 by tension rods 23. One or more containers or pots 24 is slidably and swingably mounted on the rods 23 by bearings 25 provided with 10 arms 26 supporting the containers upon trunnions 27. In the present apparatus there are two containers convenient for the use of two operators—one on either side of the machine—but more or less containers may be 15 provided if desired. Collars 28 rigid with the rods 23 limit the lower position of the containers so they will swing clear of the top of the platform 21 when down. To assist the operator in swinging the container, a handle 29 may be pivoted at 30 to allow it to be 20 raised to a horizontal position.

In Figure 4 the container assembly comprises the container 24 proper and a plunger 35 which is movable through the container 30 cavity 36. As seen in Figure 6, the cavity is in the cross-sectional shape and size of the wheel blank to be formed and includes a rim portion 36r, spoke portions 36s and a hub portion 36h. The portions are divided to 35 form the reticulated blank by spaced sectors of metal 34 secured to the bottom of the container. The plunger 35 likewise has the cross-sectional shape of a wheel blank and closely fits the container cavity, having corresponding rim, spoke and hub portions.

The rim portion 35r of the plunger is made quite deep to take the heavy pressures imposed and the webs 35s joining the rim portion and the hub portion 35h are likewise 45 made deep and sloping at the bottom edge for greater strength. The hub portion and the inner ends of the spoke webs are secured to a central plunger rod 37, which fits in an enlarged bore in the container. This central 50 construction amply supports the hub portion and inner ends of the spoke portions of the plunger but if the depth of the rim portion is not such as to give it sufficient rigidity it may be supported between the spoke webs 55 by auxiliary plunger rods 38 secured to a base plate 39 to which the central plunger rod is secured. Holes 40 are provided in the bottom of the container to slidably receive the rods 38.

60 The plunger is secured to the container by bolts 42 attached to the base 39 and slidably passing through ears 43 on the container. A spring 44 embracing the bolts 42 and pressing against the base and ears distends the container and plunger tending to keep the

70 plunger in the bottom of the container cavity. A nut 45 on each bolt limits the separation of container and plunger. By adjustment of the nuts against the springs the normal space in the container cavity above the plunger for the reception of moldable material may be varied to suit materials of different varieties and various degrees of compressibility. For very light loose material of large volume the nuts may be let off to place the plunger in the very bottom of the container cavity to accommodate the maximum volume of material; for denser material the nuts may be taken up to raise the plunger in the cavity to take a smaller volume of material.

75 Cooperating with the container when it is swung "in the press", is a mold 46 secured beneath the press head 22 in alignment with the platform 21. The mold has a cavity 47 which comprises a rim portion 47r, spoke portions 47s and a hub portion 47h which at the lower edge exactly correspond to the size and shape of the cavity in the container. The mold cavity is rounded at the bottom somewhat and the side walls slope slightly to assist ejection of the wheel blank from the cavity after compression. In case the wheel is designed to have an axial extension the 80 mold cavity is made with a corresponding hub depression 47e. Likewise, if the wheel is to have a hub cavity, the plunger is provided with an extension 35c to form the cavity.

85 Means is provided for accurately registering the container cavity and mold cavity when brought together. This comprises an end-tapered dowel 48 on one (the mold as shown) and a conical-mouthed hole 49 in the other.

90 Means is provided for ejecting the wheel blank as a unit from the mold cavity after compression therein. As shown in Figure 4 (see also Figure 11), an ejector plate 50 is mounted in slots 51 in the head 22 and is provided with a plurality of ejector pins 52 judiciously scattered over the entire area of the cavity so as to press evenly on all parts of the blank. As seen in Figure 11 the mold is united to the head across the plate at 95 numerous places by solid metal spacers 53.

100 Disposed across the plate is a bar 54, also movable in the vertical slot, and rigidly attached at its protruding ends to actuating rods 55. The rods at their lower ends pass loosely through holes in brackets 56 secured to platform 21 and are provided on their ends with nuts 57 below the brackets. Thus the platform is perfectly free to move upward without acting upon the rods and ejector plate but comes against the nuts 57 to carry the plate down with it near the end of its return stroke. In this construction the ejector pins and plate are moved upward by 105 material being compressed in the mold cavity 110

but do not offer any appreciable obstruction thereto such as would cause the pins to make holes in the blank because there is very little weight on the pins at this time. The whole weight of platform and associated parts is effective for ejecting the blank but only the weight of plate, bar 54 and rods 55 rests on the pins and blank on the upward stroke. If this weight is objectionable, lift pins 58 may be attached to the plate to be engaged by the top surface of the container just before the container comes against the mold to lift the ejector plate and pins before any material is pressed into the mold cavity.

To prevent material which may get past the plunger from collecting in the bottom of the container cavity to restrict the retraction of the plunger, vent holes 60 may be provided from the cavity through the bottom of the container.

Ordinarily it is desirable to form a hub bore through the wheel for attaching it to a shaft. For convenience this bore is formed when the blank is formed. For this purpose a hub pin 61 is placed in a well 62 formed in the hub portion 35h of the plunger. A light spring 63 supports the hub pin to normally hold it in elevated position but there is a very slight friction between the pin and the well surface so that the pin will tend to remain in whatever position to which it may be moved by the operator.

The operation of the apparatus, in case the wheel is to be made of uniform thickness and density of rim, spokes and hub, without hub cavity or hub extension, and without reinforcement, is as follows: The container being swung out and empty, the operator pulls the hub pin 61 up to the position shown in Figure 7 and places a conical pin 64 having, if desired, a lift knob 65 into a hole 66 in the upper end of the hub pin. The conical pin aids in inserting material into the container cavity.

The operator then takes enough loose material to form the wheel and pours it into the wheel cavity, spreading it evenly with his hands. The loose material may be powdered, shredded, chipped or in any form sufficiently small or flexible to be pushed into the cavity. Herein, the term "conglomerate" is used to denote loose compressible material of any size or shape suitable for easy introduction into the reticulated container cavity and without any ordered arrangement, i. e., "helter-skelter".

Preferably if material such as wood pulp, sawdust, shavings, excelsior or powdered, comminuted or shredded paper, fabric, board or like material is used it is first saturated with an adhesive, such for example, as a phenolic condensation product adapted to cure under heat and pressure to a hard, polished, waterproof body. Such an adhesive will in the final wheel cause all particles

thereof to adhere to form a rigid strong wheel and will also form a smooth surface thereto.

Having filled the container cavity, the operator lifts the handle 29 and swings the container assembly into position between the platform and head-mold, a stop member of any desired kind being employed, if desired, to secure accurate positioning.

Hydraulic pressure is then admitted to cylinder 20 by way of inlet (and outlet) opening 67 (Fig. 4) to raise the platform 21. When the platform comes against the plunger base 39 of the container assembly it first raises the whole assembly—due to the strength of springs 44 distending the container and plunger—until the top of the container is tight against the bottom surface of the mold 46. As the container approaches the mold its upper surface engages the lift pins 58 to raise the ejector pins from the mold cavity. No material is pushed out of the container in this movement. As described, dowel 48 insures accurate registry of container and mold cavities.

Thereafter, additional hydraulic pressure is let into the ram cylinder to force the plunger through the container cavity to compress all of the material into the mold cavity to form a homogeneous, integral, one-piece or "monolithic" wheel blank which in cross section is slightly smaller than the finishing mold so as to be insertable therein. The upper end of the hub pin 61 or some part borne by it enters a hole 70 in the center of the mold to hold the pin vertical so that the wheel bore will be accurately located and so no material will be squeezed through the hole 70. The pressure is high enough to consolidate the material depending on its nature, being in some cases 10,000 pounds per square inch or over.

After full compression, the hydraulic fluid is exhausted and the ram retracted. The wheel blank remains in the mold cavity until the ram has practically completed its withdrawal. Then the weight of the platform comes upon the ejecting pins as described above to press the blank evenly and without damage from the mold. The operator may catch it in his hands and lay it on top of the container after it is ejected. It might be marred if allowed to fall freely.

The container is then swung out, the blank removed and a new charge placed in the container.

The finished blank is thereafter placed in a heated mold under high pressure and finished. The final mold thus does not need to have a very deep cavity since the blank is pre-compressed. Further than this, no assembling of parts in or building up for the final mold is required since the blank has been completely formed previously.

In case portions of the finished wheel are

to be deeper than others, more material may be placed in the blanking mold for those portions. One way of doing this is for the operator to pack the loose material down by hand in certain portions of the container cavity.

5 This is usually required for the rim and hub since they are usually thicker than the spokes. Where a very deep hub (or other portion) is required, a pre-compressed filler may be used.

10 Such a filler is used in the blank made in the press illustrated. It is best shown in Figures 4, 8 and 9, where it is referred to by the character 72. The reason for these steps will be obvious when it is remembered that all parts

15 of the plunger travel through the same length of stroke, and the normal tendency is to compress all portions of the wheel blank equally.

In case reinforcement is desired in the wheel, a portion of the loose material (about 20 half as shown) is placed in the container cavity, then the reinforcement is put in, and then the cavity is filled to the top over the reinforcement. The reinforcement illustrated comprises an annular rim ring 73r, spoke rods 25 73s, a hub bushing 74 and a hub ring 73h. In placing this wheel assembly in the container, the conical pin 64 is removed when the container is half full of loose material and the bushing placed on the top of the hub pin 61.

30 The bushing will have the hub ring placed thereon and, where the rim ring, spoke rods and hub ring are a unit as here, the whole reinforcing frame is placed on the bushing at once.

35 Then a cylindrical headed pin 75 is inserted through the bushing into the bore of the hub pin 61 and the hub pin and all parts carried thereon pushed down against the light spring 63 until the reinforcing frame 40 rests on top of the loose material in the cavity. Care, of course, is taken to see that all the reinforcing parts are spaced sufficiently

45 from the container walls so as not to be exposed or to lie near enough the surface to mar the appearance of the final finished wheel.

50 It is one of the advantages of the present invention that dislocation of the reinforcing can be detected in most cases in the blank which assures a greater percentage of perfect finished wheels. The pre-formed hub filler piece 72, which is suitably shaped and notched to fit the bushing and spoke rod assembly, is then put on and the cavity filled to the top.

55 From the above description it will be seen that the press effects a great economy in the art by reason of forming a complete wheel blank in a single operation from loose material, avoiding all pointing, forming up, winding or the like and avoiding all waste of material. Not only is immediate waste in the process avoided but it is made possible to use some waste material in a plant which would otherwise be hard to make use of. In practice the invention has tremendously reduced costs 60 and speeded up production.

The use of a press of this kind which permits the use of loose material assures better placing of moldable material in the corners and spaces about the reinforcement which gives a better bond and hence a stronger 70 wheel.

While one embodiment of the invention has been particularly described, it is to be understood that various changes and modifications may be made within the scope of the subjoined 75 claims.

What I claim is:

1. A blanking press for making spoked wheels comprising in combination, a pot or container having a deep cavity in the shape of the final wheel including connected rim, spoke and hub portions, a plunger of the same shape as said cavity positioned in the bottom thereof, a plurality of plunger rods associated with said plunger to support it at several points and adapted to pass through said pot cavity, a plate for actuating all of said rods, bolts supporting said plate on said pot, springs normally separating said plate and pot, a press ram, a press head aligned therewith, tension rods to take strain between said head and ram, said tension rods normally supporting said head apart from said ram by a distance greater than the distended length of said pot and plate, hinges supporting pots and related parts on said tension rods, said hinges providing movement of pots into alignment with said ram and clear of the same and also longitudinal movement with the ram, a molding cavity in said head, a reciprocable ejecting member in said head having a plurality of ejecting pins entering said head cavity, and lost motion rods connecting said ram and said ejecting member whereby said pins are pushed through said molding cavity to eject the blank when the ram fully withdraws.

2. A blanking press for making spoked wheels comprising in combination, a pot having a deep cavity in the shape of the final wheel including connected rim, spoke and hub portions, a plunger of the same shape as said cavity positioned therein, a central plunger rod and a plurality of surrounding plunger rods associated with said plunger, a plate associated with the outer ends of all of said rods to actuate them together, means holding said plate and pot in separated relationship, a press ram, a press head aligned therewith, means supporting said pot for movement from a position between said ram and head and a position clear of the same, a molding cavity in said head, a reciprocable ejecting member in said head having a plurality of ejecting pins entering said head cavity, and means for operating said ejecting member when the ram withdraws for ejecting the compressed wheel blank.

3. In a press for molding spoked wheels in combination a container, a plunger fitting

therein, a mold registering with the cavity of said container into which loose material placed in the container is to be compressed, an ejector provided with spaced pins entering 5 the cavity of said mold, other pins positioned to contact with the upper face of said container outside of the cavity thereof for removing said first mentioned pins from the mold cavity when the mold and container are 10 brought together whereby the ejecting pins do not act upon the material until after it has been compacted.

In testimony whereof, I have signed my name to this specification this 4th day of October, 1929.

GRANT E. SMITH.
